UNITED STATES PATENT OFFICE.

WILLIAM O. WHITE, OF LAKE VILLAGE, AND WARREN D. HUSE, OF LACONIA, NEW HAMPSHIRE.

STEAM-TRAP.

SPECIFICATION forming part of Letters Patent No. 278,381, dated May 29, 1883.

Application filed January 15, 1883. (No model.)

To all whom it may concern:

Be it known that we, WILLIAM O. WHITE, of Lake Village, and WARREN D. HUSE, of Laconia, in the county of Belknap and State 5 of New Hampshire, have invented an Improved Steam-Trap; and we do hereby declare that the following is a full and exact description thereof, reference being had to the accompanying drawings, making a part of this 10 specification—

Figure 1 being a central longitudinal vertical section of a double steam-trap constructed with a part of our improvements; Fig. 2, a cross-section in a plane indicated by the line 15 *xx*, Fig. 1; Fig. 3, a cross-section in a plane indicated by the line *yy*, Fig. 1; Fig. 4, a view in central vertical longitudinal section of the invention as applied in the construction of a single trap; Fig. 5, a section showing the 20 construction as arranged with an adjustable valve-seat; Fig. 6, a side view of a trap acting on the same principle, and provided with a means for multiplying the expansion movement; Fig. 7, one end view of the same; Fig. 25 8, an opposite end view thereof; Fig. 9, a section through the trap-case, showing the interior construction of the trap.

Like letters designate corresponding parts in all the figures.

Our improved steam-trap in its simplest form, which we term a "globe-valve trap," is composed of a simple short pipe, in which the condensed steam collects, through which it passes, and from which it is discharged, acting, as to the first part of our invention, in combination with a fixed, solid, plane-faced, or equivalently-formed valve-seat, against which one end of the said pipe or valve-stem abuts. The said valve-pipe being located in the open 35 air, and having no operative mechanical connection whatever with the steam pipe or pipes which it drains, and not being affected by the contraction and expansion thereof, no additional valve action is required, and the valve-seat itself may be placed in the open air, being 40 inclosed in a case or shell only for convenience in mounting, and for attaching a drain-pipe to carry off the condensed water discharged from the trap. For these purposes, therefore, we 45 find it desirable to make the case or shell of 50

the valve-seat in the general form of a globe-valve. The whole trap is consequently exceedingly cheap in construction as well as effective in operation.

As to the second part of our invention, it 55 consists in such a valve-pipe and a similar solid, plane-faced, or equivalent form of seat, which is movable, and connected by leverage with the valve-pipe, so that the motion resulting from the contraction and expansion of the 60 pipe is also communicated to the valve-seat in such a manner as to act in the opposite direction to that of the valve-pipe, the lever-connection also being adjustable, so as to multiply the rapidity of the approach and separation of the valve and seat to any extent desired. 65

Since in this invention the valve-seat A (referring to the accompanying drawings) is always fixed, we are enabled, when desirable, 70 to make one valve-seat serve for two valve-pipes, B B', as shown in Fig. 1, one valve-pipe, B, abutting and shutting against one side, *a*, of the seat, and the other valve-pipe, B', abutting and closing against the other 75 side, *a'*, of the seat. Both valve-pipes may thus also be drained by one drain-pipe, C. This principle may be carried still further to any practicable extent by having three or more valve-seat surfaces in one and the same case 80 D, facing in different directions. A single seat, however, may just as well be used, as shown in Fig. 4, and in some cases only a single trap is wanted at a particular place. The globe-valve case D is or may be provided 85 with suitable ears or flanges, *b b*, for securing it to a wall or other support. The valve-pipe B is mounted near its receiving end in a bracket, E, which is secured by screws at *c* or other means to the wall or other support. 90 We make the valve-pipe adjustable in this support for the purpose of properly adjusting the position of the pipe in relation to its valve-seat A, according to the pressure of steam employed in the steam apparatus, the inner 95 end of the pipe fitting tightly against the valve-seat when in contact therewith. For the purpose of this adjustment we employ the construction represented or an equivalent means. As shown, it consists of a short sleeve or 100

larger pipe, G, fixed upon the valve-pipe and screw-threaded on its periphery, so as to work in an aperture in the bracket E, which is screw-threaded, as a nut, to receive it. In this screw-sleeve, near one end, there are pin-holes *d d*, by which to turn the sleeve and pipe for producing the required adjustment of the pipe; or any other convenient and suitable means may be employed for applying a wrench or other instrument to turn the screw-sleeve. The outer end, *f*, of the valve-pipe fits in a stuffing-box, H, which also connects or is joined in one, as shown, with one or more stuffing-boxes, I, by which the steam pipe or pipes K may be brought into communication with the valve-pipe B. The expansion and contraction of such steam-pipe in its stuffing-box I are entirely free from, in action, and do not affect, the said valve-pipe. The valve-pipe B for the second or any additional trap connected with the first is to be mounted, made adjustable, and connected with its steam pipe or pipes in the same way as described for the pipe B. The valve-pipe B is preferably made of copper, for obvious reasons, although we do not confine ourselves to any special material.

The section, Fig. 5, shows an adjustable valve-seat, A, for a single trap, the seat screwing into the case and being held securely in any position to which it is adjusted by a jam-nut, *g*.

In Figs. 6, 7, 8 and 9 we show a construction of the trap by which the movement resulting from the expansion of the pipe is doubled or multiplied to any desired extent within proper limits, whereby the trap is made still more sensitive and quick in its operation. We here make the seat A also movable toward and from the expansion valve-pipe B, and connect the pipe and seat by a lever or other connection, so that the lengthening or shortening movement of the pipe in expanding or contracting is communicated to the seat, multiplying the motion also, if desired, in such a manner that the movements of the pipe and seat are added to produce the effect of closing or opening the valves—that is, the two approach each other or recede from each other at the same time.

Referring to the drawings, the valve-pipe B and valve-seat A are shown arranged in line with each other, and the seat and one end of the pipe are mounted in packing or other extensions, *h h*, of the case. Two lugs or flanges, *i i*, also project from the case, on opposite sides of the same, and from these lugs, respectively, extend rods *j j* along parallel with the valve-pipe to a bracket or clamp, E, which holds the outer end of the pipe. These rods extend through the ends of the clamp, and are provided with adjusting-nuts *k k*, by which the distance between the clamp and the trap-case is adjusted. The pipe B is held firmly by this clamp, a clamp jaw or bar, *l*, being pressed against the pipe by set-screws *m m* or their equivalent. Thus the position of the pipe in

relation to the valve-seat is adjusted in a manner equivalent to the means shown in Figs. 1 and 4. The valve-seat A is or may be provided with a screw-stem, *n*, to allow the said valve-seat to be located in just the position desired. With this stem a lever, M, is connected at one end, and may be adjusted in place thereon by adjusting-nuts *o o*. The lever has its fulcrum on an arm or a bracket, N, which is suitably mounted on the trap-case D in the manner shown or otherwise. The other end of the lever is pivoted to a connecting-rod, O, which at the other end is connected with a clamp-piece, P, secured fixedly to the valve-pipe B, as near to the trap-case D as practicable, so as to obtain the advantage of as much of the expanding and contracting pipe as possible for moving the lever M. The connecting-rod O may be adjustable to different positions on the lever, as shown by the different pivot-holes *p p*, so as to multiply the motion transmitted from the pipe to the lever as much as desired in its action on the valve-seat A. Any equivalent means of transmitting motion from the valve-pipe to the valve-seat, so as to make them move in opposite directions and to increase their combined movements to the desired extent may be adopted. These combined actions of the valve pipe and seat make an exceedingly sensitive and effectual steam-trap.

What we claim as our invention, and desire to secure by Letters Patent, is—

1. In a steam-trap, a valve-pipe, B, separate from and unaffected by the expansion and contraction of the pipe or pipes which it drains, communicating with the said pipe or pipes by a suitable stuffing-box held fast by a separate bracket or holder near the said stuffing-box, and held in position near its other end and allowed a free longitudinal movement at that end, in combination with a solid plane-faced valve-seat, substantially as and for the purpose herein specified.

2. A double steam-trap composed of two valve-pipes, B B', and a single valve-seat, A, substantially as and for the purpose herein specified.

3. The combination of the valve-pipe B, provided with a screw-threaded sleeve, G, the screw-threaded bracket E, valve-seat A, and case D, substantially as and for the purpose herein specified.

4. In a steam-trap, the combination of the valve-pipe B, the double or compound stuffing-box H I, and steam pipe or pipes K, substantially as and for the purpose herein specified.

5. In a steam-trap acting by the lengthening and shortening of a pipe or tube which closes against a seat to form the water-discharge valve, the combination of the valve-pipe with a movable seat connected mechanically with the pipe, whereby the motion resulting from the contraction and expansion of the pipe is also communicated to the seat, to increase the rapidity of the approach and sep-

aration of the pipe and seat, substantially as and for the purpose herein specified.

6. The combination of a valve-pipe, B, operating as described, a movable valve-seat, A, a lever, M, and connecting-rod O for communicating the expanding and contracting movement of the pipe to the seat, substantially as and for the purpose herein specified.

7. The combination of the valve-pipe B,

movable valve-seat A, lever M, having a variable leverage, and connecting-rod O, substantially as and for the purpose herein specified.
